John Enders

Inventor:
Fred Wesley Cook,
by Robert Burns.

UNITED STATES PATENT OFFICE.

FRED WESLEY COOK, OF NORTH CHICAGO, ILLINOIS, ASSIGNOR TO CHICAGO HARDWARE FOUNDRY COMPANY, OF NORTH CHICAGO, ILLINOIS, A CORPORATION OF ILLINOIS.

TABLE OR STAND.

1,380,042.

Specification of Letters Patent. Patented May 31, 1921.

Application filed February 4, 1921. Serial No. 442,345.

To all whom it may concern:

Be it known that I, FRED WESLEY Cook, a citizen of the United States of America, and a resident of North Chicago, in the 5 county of Lake, State of Illinois, have invented certain new and useful Improvements in Tables or Stands, of which the following is a specification.

This invention relates to means for attaching together the end standards or legs and the intermediate horizontal connecting brace of tables and like support, and has for its object:

To provide a simple, durable and substantial structural formation and combination of parts whereby a connection in a strong and effective manner is attained between the brace and the legs, and with which the fastening devices are concealed from view and 20 a smooth surface appearance of the parts at the points of juncture is attained, all as will hereinafter more fully appear.

In the accompanying drawing:—

Figure 1, is a perspective view of a lunch 25 room table illustrating the general arrangement of parts in the present invention.

Fig. 2, is an enlarged detail vertical section on line 2—2, Fig. 3, of the present connecting means.

30 Fig. 3, is a detail horizontal section on line 3—3 Fig. 1.

Like reference numerals indicate like parts in the different views.

Referring to the drawing, 1 designates the 35 usual rectangular upper frame of a table or stand upon which the table top 2 is supported.

3, 3 designate pairs of end legs, preferably of a curved form and having adjacent relation at their mid-height as shown in Fig. 40 1, and with each leg of a V form in cross-section as illustrated in Fig. 3.

4, designates a horizontal tie member arranged midway the height of the legs 3 and 45 preferably of a channel shape in cross-section and formed with expanded end portions 4' formed with orifices in their vertical walls for the passage of attaching lugs of the legs, and for the shank of the attach-

ing bolts of the present construction more to 50 be described.

5 designates counterpart orificed lugs formed as integral parts of the legs 3 and projecting inwardly therefrom. Said lugs are adapted to project one past the other in 55 an assembled condition of the parts with their orifices in alined relation to receive the attaching bolts now to be described.

6 designates an attaching bolt having an outer fixed head 6' adapted for bearing 60 against an end wall of the brace member 4 with the shank portion of the bolt passing through an end orifice of said brace and through the alined orifices of a pair of legs 65 3 to receive a clamping nut 7 by which the parts are drawn together and firmly held in assembled relation.

In the preferred form of the present construction, as shown more particularly in Fig. 3, the attaching lug 5 of each leg 3 has 70 an offset arrangement so that its inner vertical face will be on the median vertical line of the leg. With such construction, legs of a single counterpart formation can be employed in that when arranged in reversed 75 relation for assemblage the lug 5, of one leg will pass the lug 5 of the companion leg into proper assembly position.

Having thus fully described my said invention what I claim as new and desire to 80 secure by Letters Patent is:—

1. In a table or the like, the combination of a pair of opposed legs formed with orificed lugs, a horizontal brace having enlarged hollow ends formed with orifices for 85 the passage of said lugs, and an attaching bolt passing through an end orifice in said brace end and through the orifices of the aforesaid lugs and having a fixed head at one end and a clamping nut at the other 90 end.

2. In a table or the like, the combination of a pair of opposed legs formed with orificed lugs, a horizontal brace of a channel form closed at its ends and having orifices 95 in its vertical walls for the passage of said lugs, and an attaching bolt passing through an end orifice in said brace and through the

orifices of the aforesaid lugs and having a fixed head at one end and a clamping nut at the other end.

3. In a table or the like, the combination of a pair of opposed legs formed with orificed lugs each offset from the median line of the leg, a horizontal brace having enlarged hollow ends formed with orifices for

the passage of said lugs, and an attaching bolt passing through an end orifice in said brace end and through the orifices of the aforesaid lugs and having a fixed head at one end and a clamping nut at the other end. 10

Signed at North Chicago, Ill., this 31st day of December, 1920.

FRED WESLEY COOK.
